UNITED STATES PATENT OFFICE

VIOLA BERRYMAN AND GIDEON C. HOXIE, OF CONCORD, CALIFORNIA

SLIDING SCREEN CONSTRUCTION

Application filed January 11, 1928. Serial No. 245,947.

Our invention relates to improvements in sliding screen construction wherein screened frames are slidably mounted for movement between a track and guides carried by a mounting frame set within a wall around a window opening and forming pockets into which the screened frames may be moved to uncover the window opening and to conceal and protect the screens.

10 The primary object is to provide an improved construction for sliding screens.

Another object is to provide an improved construction which will facilitate the installation of screened frames for windows.

15 A further object is to provide an improved arrangement whereby the screens may be readily moved to uncover a window opening and which will permit the quick and easy movement of such screens to and from a concealed, inoperative position within pockets formed in the wall at the sides of a window.

20 Another object is to provide an improved construction which will form a fly-proof closure and which will permit the complete removal of the screened frames if desired.

25 A still further object is to provide an improved frame which may be installed in the wall of a building in connection with a window casement to permit a sliding movement of screened frames into pockets formed at the sides of the window without weakening the building frame around the window.

Our invention consists of the details of construction and arrangement disclosed in the 35 drawings forming a part of the present application wherein like characters of reference are used to designate similar parts throughout the specification and drawings and in which—

40 Fig. 1 is a front elevation of our improved sliding screen construction as installed in connection with the frame of a wall;

Fig. 2 is a perspective view of the screen 45 mounting frame;

Fig. 3 is a horizontal sectional view showing the plan of the lower frame member;

Fig. 4 is a horizontal sectional view showing the bottom plan of the upper frame 50 member;

Fig. 5 is a broken transverse sectional view drawn upon a larger scale;

Fig. 6 is a broken detail showing the manner in which the screen frames are supported upon the track; and

Fig. 7 is a broken sectional detail drawn upon a still larger scale showing the manner in which the lower edge of the screen frame is constructed and mounted to form a fly-proof closure.

Referring to the drawings, the numeral 1 is used to designate in general the portion of a building frame immediately surrounding a window opening. Within, and in connection with said building frame 1 is provided a screen mounting frame consisting of upper and lower longitudinal members 2 and 3 positioned above and below the window opening. The members 2 and 3 are notched as at 4 to receive pairs of vertical studs 6 at the sides of the window openings. The ends of the members 2 and 3 extend into the wall frame at each side of the window opening and are connected at their extreme ends by vertical members 7. Vertical members 8 are connected between the members 2 and 3 adjacent the studs 6, said members being arranged in spaced pairs to cover the studs and to form a casement facing for the sides of the window casement. The central portion of the upper member 2 is made somewhat wider than the ends of said member and forms a facing for the top of the window casement. The vertical members 7 and 8 are preferably mortised into the longitudinal members 2 and 3 as best shown in Fig. 2 of the drawings.

Screen frames 9 having suitable screening 55 secured thereon, are slidably mounted within the screen mounting frame between the upper and lower members 2 and 3 thereof. The screened frames 9 are slidably supported upon a track 12 secured upon the upper side of the lower member 3, suitable flanged rollers 14 being preferably inset within the lower edges of the frames 9 to facilitate movement of the frames along the track. Guide members 16 are secured upon the under side of the top member 2 to engage and guide the upper edges of the frames 9. The lower edge of each frame 9 is provided with a depending 60

flange 17 formed upon the outer lower edge and arranged to overhang the track 12 and effect a fly-proof closure along the lower edge of said frame 9. The inner edge of each frame 9 is arranged in a plane above the top 5 of the track and is arranged to abut against the edge of a sill 18 mounted between the casement members 8 to effect a further closure along the inner lower edge of said frame. Sufficient clearance is afforded between the 10 top of each frame 9 and the upper longitudinal frame member 2 when the frames are properly supported upon the track 12 to permit said frames to be lifted clear of the track and moved outwardly at the bottom to dis- 15 engage the track when the frames are moved to a central position within the window opening.

The screened frames 9 are made of a width 20 such that together they will occupy a width slightly greater than the width of the window opening. A stop 19 is removably secured upon the upper longitudinal frame member 2 at the center thereof to define the operative 25 closing positions of the screens and to limit the movement of said screened frames toward each other. When moved to closing position, the adjacent edges of the frames meet at the center of the window opening and the 30 frames extend to the sides of the opening and are received between the spaced pairs of vertical members 8 and the studs 6, the side members of the screen frames 9 being arranged to substantially close the space between the studs 6 and members 8 and thereby 35 effect a closure at the sides of the window when the screens are in closed position. The frames are arranged to be moved along the track 12 into pockets formed within the wall by the frame members 2, 3, and 7, as shown 40 at the right in Figs. 1 and 3 of the drawings, said pockets being of a size such as to permit the screens to be moved entirely into the wall with the inner outer edges of the 45 frames in substantially matching relation with the face of the casement members 8.

In operation, the mounting frame is installed around the window opening during the construction of the building wall. When 50 the frame and casement is completed, the screened frames 9 are mounted by moving the screen into position from the outer side and raising the lower edge sufficiently to move the rollers 14 onto the track. After 55 the frames 9 are placed, the stop 19 is mounted in proper position to define the operative position of the screens and prevent the frames from being moved to clear the casement members 8, said members 8 serving 60 to prevent the frames from being removed from the mounting frame. The screened frames may now be moved at will to extend across and cover the window opening, or moved to inoperative position within 65 the pockets formed in the walls. In the latter

position, the screens are fully concealed and protected from exposure. When in operative closing position, the window opening is fully screened and a fly-proof closure is effected entirely around the window. If it is desired to remove the screened frames from their mounting frame, the stop 19 is removed. The screens may then be moved one at a time to clear the ends of the window casement and they may then be lifted and moved outwardly at the bottom to disengage the track. 70 75

In the drawings, we have illustrated our invention as applied in connection with windows of the hinged type. The invention however may be applied in connection with windows of other types by slight modification in a manner obvious to any person skilled in the art. While our invention is directed primarily to the specific construction illustrated and described, we are aware that modification can be made in numerous details without departing from the spirit of the invention and we desire to avail ourselves of all such modifications as may fall 80 85 within the scope of the appended claims. 90

Having thus described our invention what we claim as new and desire to secure by Letters Patent is—

1. In a sliding screen construction, a 95 mounting frame arranged to be set within a wall around a window opening therein, said frame consisting of upper and lower longitudinal members arranged above and below the window opening and extending 100 into the wall at each side of the window opening, said members being notched to receive studding mounted at each side of the window opening; upright members secured between the longitudinal members and forming pockets within the wall and frame at the sides of the windows; and screened frames 105 slidably mounted within the frame and slidably movable into and out of said pockets to cover or uncover the window opening as desired. 110

2. In a sliding screen construction, a mounting frame arranged to be set within a wall around a window opening therein, said frame consisting of upper and lower longitudinal members arranged above and below the window opening and extending into the wall at each side of the window opening, said members being notched to receive studding mounted at each side of the window opening; upright members secured between the longitudinal members and forming pockets within the wall and frame; a track secured upon the lower longitudinal frame member; guides secured upon the upper frame member; and screened frames supported upon the track and engaged upon their upper edges by the guides, said screened frames being slidably movable into and out of the pockets to cover or uncover the window opening as desired. 115 120 125 130

3. In a sliding screen construction, a mounting frame arranged to be set within a wall around a window opening therein, said frame consisting of upper and lower longitudinal members arranged above and below the window opening and notched to receive pairs of spaced studding at the sides of the window opening, the upper member having a wide central portion forming a window casement member and having reduced extensions extending into the wall at the sides of the window opening; upright members mounted between the ends of the longitudinal frame members; upright casement members mounted in spaced pairs between the longitudinal members at the sides of the window opening to cover the studding; a track mounted upon the lower longitudinal frame member; guides mounted upon the upper longitudinal frame member; and a pair of screened frames supported upon the track and engaged at their upper edges by the guides, said screened frames being slidably movable along the tracks between the pairs of studding and upright casement members and into pockets formed within the wall by the mounting frame. 75
4. In a sliding screen construction, a mounting frame arranged to be set within a wall around a window opening therein, said frame consisting of upper and lower longitudinal members arranged above and below the window opening and notched to receive pairs of spaced studding at the sides of the window opening, the upper member having a wide central portion forming a window casement member and having reduced extensions extending into the wall at the sides of the window opening; upright members mounted between the ends of the longitudinal frame members; upright casement members mounted in spaced pairs between the longitudinal members at the sides of the window opening to cover the studding; a track mounted upon the lower longitudinal frame member; guides mounted upon the upper longitudinal frame member; a pair of screened frames supported upon the track and engaged at their upper edges by the guides, said screened frames being slidably movable along the tracks between the pairs of studding and upright casement members and into pockets formed within the wall by the mounting frame; and a central stop mounted upon the frame to limit the movement of the screened frames and normally prevent movement of either screened frame past a central operative position. 80
5. In a sliding screen construction, a screened frame; a track supporting the frame; and a depending flange formed upon the outer lower edge and over-hanging the track, said flange co-acting with a sill abutting against the inner lower edge of the frame 85

to form a fly-proof closure along the lower edge of the frame.

In witness whereof, we hereunto set our signatures.
